UNITED STATES PATENT OFFICE.

JOHNSON H. BEARD, OF PROVIDENCE, KENTUCKY.

FIRE-PLACE.

SPECIFICATION forming part of Letters Patent No. 224,129, dated February 3, 1880.

Application filed July 2, 1879.

To all whom it may concern:

Be it known that I, JOHNSON H. BEARD, of Providence, in the county of Webster and State of Kentucky, have invented a new and 5 Improved Fire-Place, of which the following is a specification.

The object of my invention is to provide a portable fire-place that will be self-supporting when it is set up, and does not require any 10 other support to give it stability.

In the drawings, Figure 1 represents a front elevation; Fig. 2, a vertical cross-section on the line $x-x$; Fig. 3, a plan view, showing the 15 position of the ribs and holes in hearth-plate.

Similar letters of reference indicate corresponding parts.

A is a hearth-plate, of cast or wrought iron, provided with the ribs B B. These ribs are provided so that the hearth-plate can be made 20 very light, but yet have sufficient strength. $e' e' f' f' d' d'$ are the holes into which the hooks or pins of the different parts fit, as will be hereinafter described.

F is the back plate, made of cast-iron, and 25 of such size and form as to give a good draft. It is provided with two or more hooks, $f f$, which take in the holes $f' f'$. D is the fire-place front, made of sheet or cast metal, and has a large opening, O, and is provided with 30 four or more hooks, $d d$, which take in the holes $d' d'$ in the hearth-plate A.

E E are the jambs, one on each side of the 35 grate, and provided with the hooks e and s . The hooks e take in the holes $e' e'$ in the hearth-plate A, and the hooks s take in the holes s' in the back plate. The fire-place front D is secured to the jambs by means of the screws K K.

H H are the front longitudinal bars of the 40 grate, and fit into the notches N and P in the jambs E E. G G are the cross-bars of the grate, and rest on the lower bar, H, and on the rear cross-bar, H'.

C is the folding fender, provided with the 45 hinges M M at the corners, and with the pins $c c$ at the ends of the side pieces. These pins fit into the holes $c' c'$ in the fire-place front D.

The fire-place is set up in the following manner: The back plate, F, is set up first by passing the hooks $f f$ into the holes $f' f'$; 50 then the jambs are placed in position by passing the hooks $e e$ into the holes $e' e'$ in the hearth-plate and the hooks $s s$ into holes $s' s'$ in the back plate, F. Next the grate is secured by resting the ends of the bars H H in the notches N and P. The fire-place front is then set up by passing the hooks $d d d d$ into the holes $d' d' d' d'$ in the hearth-plate A and uniting it with the jambs E E by means of the screws K K. The fender is then secured 60 by passing the pins $c c$ into the holes $c' c'$ in the fire-place front D. All parts are thus well fastened to each other, and cannot move or shake, and the fire-place now stands firm and 65 secure, and need not be supported by any other object. By a reversal of these steps it can be taken apart and laid away until again required.

The hearth-plate, fire-board, and fender can be used without the other parts for wood-fires. 70

Having thus described my invention, I claim as new and desire to secure by Letters Patent—

The combination of the hearth-plate A, provided with holes $d' d' e' e' f' f'$, and of fire-place front D, having two or more pins, d , of back plate, F, having pins f , and of jambs E, having pins $e e$ and $s s$, as and for the purpose set forth. 75

JOHNSON H. BEARD.
